CLOSURE PLUG

Herbert P. Scnof, 695 Parkway Ave., Trenton, N.J.
Filed May 16, 1962, Ser. No. 195,238
1 Claim. (Cl. 220—39)

This invention relates to closure plugs for containers and methods for making the same, and is more particularly concerned with the combinations of plug bodies with means for actuating the plugs and methods for forming such combinations.

Where threaded closure plugs, particularly those principally designed for use in the closing of openings in large containers, are made of relatively lightweight metal, the problem of providing them with the proper actuating means becomes acute. The forces exerted in applying and tightening such closure plugs are often considerably greater than necessary for effective closing. Thus, unless the plugs are properly constructed, the application of excessive forces, instead of providing a tight closure can result in distortion of the plug and consequent leakage.

Accordingly, in providing wrenching means, adequate strength must be provided in the means itself, the means must be engaged with the plug in a manner of comparable strength and, at the same time, protection of the plug against distortion must be taken into consideration. Nevertheless, the whole construction must provide a simple, economical, effective closure in order to make it commercially attractive. All these criteria of an effective closure plug are met by the instant invention.

It is accordingly an object of this invention to provide lightweight closure plugs with effective wrench-engaging means.

Another object is to provide for a strong engagement between the wrench-engaging means and the plug.

Still another object is to provide for such engagement in a manner to protect the plug against distortion when actuated.

Further objects are to provide methods for forming the plug inserts carrying the wrench-engaging means and for assembling such inserts with the plug body in simple economical manner.

Still further objects will in part be obvious and in part be pointed out as the description of the invention, taken in conjunction with the accompanying drawing, proceeds.

In that drawing:

FIGURE 1 is a fragmentary plan view of a plug, in accordance with the invention, embodying the FIGURE 3 insert, and showing surrounding portions of a container.

FIGURE 2 is a fragmentary sectional view as seen from the plane 2—2 on FIGURE 1.

FIGURE 3 is a perspective view of the insert in finished form, ready to be assembled with the plug body.

FIGURE 4 is an exploded elevational view of the insert and the plug body.

FIGURE 5 is an elevational view, partly broken away of the insert and plug body with one form of wrench in place.

FIGURES 6 and 7 are vertical sectional views as seen from the planes 6—6 and 7—7 on FIGURE 4.

Considering first the body of the plug, the same has a base or bottom 1, an upstanding threaded side wall 2 therearound, and a depressed gasket seat 3, the head of the threads carrying the gasket 4. Above that gasket seat, forming one border thereof, is the head 5. The head 5 extends outwardly at the upper border of the gasket seat 3.

The threading of the side wall of this plug is shown as being of the rolled type. Such threading is provided by the roller swaging of thin sheet metal, saving considerable metal by enabling plugs to be formed of lighter stock than is required where the threads are cut into the metal. By the same token, the lighter material, though fully

2

effective for proper closing, is more easily distorted in response to excessive torque than are the so-called "cut thread" plugs. It is hence desirable that the means employed for actuating the plug does not impart its torque to any particular section of the threads but that, instead, the torque is distributed all over the plug. It is further and at least equally desirable that no operative distorting action be transmitted to the gasket seat or head. The actuating member of this invention and the manner of applying the same meet these requirements.

The actuating member 44 is preferably fabricated by cutting and forming from flat sheet metal, preferably steel. The body 10 thereof has a center portion 11 having securing portions 12. Depressions 14 are formed in the stock of the portions 12 adjacent the outer edge of that stock. These, being caused by a pressing operation, produce projections 15 on the bottom side of the body 10, as seen in FIGURE 4. The projections or pimples 15 serve to localize the welding current employed in securing the actuating member in place in the plug body. Their position, immediately adjacent the protuberances 60 and 62, is of importance, as will appear hereinafter.

The actuating member 44 includes the base 53 and the pair of upwardly directed hollow protuberances 60 and 62. The base 53 has central longitudinal edges 64 and 66 and curved end edges 68 and 70. The protuberances 60 and 62 are fabricated by upwardly deforming the material of the base to provide substantially right angle bends 72 and 74, the generally semicylindrical vertical wall portions 76 and 78, the rounded bends 80 and 82, and the partial domes 84 and 86.

The deformation and the stressed condition of the material forming the protuberances 60 and 62 and the rounded non-acute metal formation at the bends 80 and 82 produce great strength and resistance to distortion particularly in relation to the thickness and composition of the material of which the secondary plug element is made. Furthermore, the acuteness of the substantially right angle bends 72 and 74 produce a flat shape thereat in the vertical wall portions 76 and 78 which affords maximum area engagement with the wrench 61 thereby distributing the torque and avoiding deformation of the protuberances 60 and 62.

The base 53 is provided with an integral loop 88 produced by cutting a pair of spaced and parallel slits 89 and forcing the intervening strip of metal upward into an upwardly convex configuration. Through the loop 88 may be passed a wire or string from a label tag or the like for indicating contents, destination, et cetera.

50 In FIGURE 3 the actuating member is shown in its completely formed state, ready for application to the plug body.

There are important features to be noted here. They can best be seen by reference to FIGURE 1, where the insert is shown seated within the hollow of the plug. In the first place it will be seen that the actuating member, as formed from the body 10, extends substantially the whole way across the interior of the plug body. Next the welding portions 14 are spaced widely apart with respect to the bottom 1 of the plug and are located as close toward the periphery of the bottom as can be reasonably accomplished. Turning forces applied to the actuating member and transmitted through the welded joints are distributed widely over the bottom of the plug and through the body of the plug. Hence distortion of the plug, through actuation of the same, is kept at a minimum.

From FIGURES 1 and 3 it is seen that a strong protuberance construction is presented for the wrench-engaging ends of the actuating member. In the forming of these ends the metal employed has been integrally deformed with the grain structure thereof strengthened by the drawing orientation. Further, the semicylindrical

wall portions 76 and 78 being substantially normal with respect to the upper surface of the base 53 offer a maximum of wrenching purchase and engagement surface, thus presenting a substantial area for engagement by the wrenching means 61 to substantially prevent distortion of the ends until the metal thereof is sheared.

An important feature of the present invention is that the plug insert or actuating member is formed from a metal blank which is only slightly larger than the finished part, with resultant lower cost and weight than comparable 10 prior art structures.

The actual welding of the actuating member within the plug body is illustrated in FIGURE 2. Here the weld 28, resulting from the projections 15 to the base 1 of the plug is shown. This welding, due to the provision of the current localizing projections, is very quickly and simply accomplished.

The completed actuating member is merely dropped into the hollow head of the plug body where, due to its size and formation, it necessarily adopts a proper position. A welding electrode is then introduced into the plug head to seat on the actuating member and overlie the localizing positions. The bottom 1 of the plug body is in contact with the other electrode of the welding system. It is merely necessary then to apply sufficient pressure between 25 the opposed electrodes to hold the actuating member and plug body together while, at the same time, passing a welding current therethrough. In this manner a quick effective joint is made.

It is to be noted that in the event the sealing of the 30 plug in position in an opening is to be accomplished by lead and wire seal, no special perforation of any portion of the plug is necessary. All one needs to do is to pass the wire under through the loop 38. In accordance with the present invention, the freedom from any holes in the 35 protuberances 60 and 62 leaves their basic strength un-

impaired. Furthermore the open ends of the protuberances 60 and 62 allow free drainage of chemical plating solutions leaving the parts clean and properly plated so that later corrosion is inhibited.

Though in the foregoing description and in the accompanying drawing a preferred form of the invention has been shown and described, it is to be understood that the article and method, so disclosed, are presented for illustrative and not limiting purposes.

Having disclosed the invention, what is claimed as new, and desire to secure Letters Patent for, is:

In a closure plug including a base, an upstanding side wall therearound, and an actuating member including a center planar base portion and upwardly extending protuberances adjacent the base portion, the improvement comprising: the center planar base portion having outer edges; a curvilinear bend portion being adjacent the outer edges; the protuberances including a generally curvilinear vertical wall portion interconnected to the curvilinear bend portion; and a partial dome portion being interconnected to said wall portion; said wall portion and dome portion forming a continuous free edge juxtaposing the inner surface of the side wall of the closure plug.
